Filed May 12, 1975, Ser. No. 576,319

Term of patent 14 years

Int. Cl. D17—03

U.S. Cl. D56—1 A

FIG. 1 is a front elevation view of a truss rod cover for guitar or similar article showing our new design;

FIG. 2 is a side elevational view of the left side thereof;

FIG. 3 is a side elevational view of the right side thereof;

FIG. 4 is a back elevational view thereof; and

FIG. 5 is a view of the top end thereof.

The bottom view thereof is a mirror image of the top view and has therefore not been shown.

We claim:

The ornamental design for a truss rod cover for guitar or similar article, substantially as shown and described.
